UNITED STATES PATENT OFFICE.

OLIVER POCOCK, OF CINCINNATI, OHIO.

MACHINE FOR BENDING SHEET METAL.

SPECIFICATION forming part of Letters Patent No. 357,228, dated February 8, 1887.

Application filed August 16, 1886. Serial No. 211,004. (No model.)

To all whom it may concern:

Be it known that I, OLIVER POCOCK, of Cincinnati, Hamilton county, Ohio, have invented new and useful Improvements in Machines for Bending Sheets of Metal, of which the following is a specification.

My invention relates more particularly to that class of machines in which rollers are used, between which sheets of metal are passed to cause said sheets to assume a curved form, but is capable of other and more general application.

The nature of my invention consists in the combined means for approximating and separating the rollers, so as to allow the device to accommodate metal of different thicknesses, and also to bend the metal in a curve of any desired radius, and the means for adjusting and holding said rollers at any distance apart that may be desired.

My invention accomplishes these ends more accurately and rapidly than any of the ordinary machines now in use, by the means fully explained hereinafter.

In the drawings accompanying this specification, Figure 1 is an end elevation of my machine, showing the arrangement of the ends of the rollers in relation to each other and the means of operating and adjusting them. Fig. 2 is a side elevation with a section broken to show the position of the third roller. Fig. 3 shows an eccentric-journal with a cored handle and a sliding catch operated by a spiral spring.

A, A', and A² are rollers, and a a' a² are the ends of the rollers. The end a is journaled in the movable box B, which is operated by the adjusting-screw b. The end a' is journaled in an immovable box in the standard C, and the end a² is journaled in the eccentric B', which is constructed to turn in the standard C, and is operated by the cored handle E, which is connected with the eccentric B', with the sliding catch F and spiral spring e, and is adjusted to any degree of curvature by means of the notched and indexed arc F'. These journals, together with the movable box B, adjusting-screw b, cored handle E, sliding catch F, spiral spring e, and notched and indexed arc F', are all duplicated at the other end of the rollers, and are fitted in a standard similar to standard C.

The roller A' is provided at one end with the

crank D, or other means for turning the roller. At the opposite end of the crank the roller is provided with a gear-wheel, d, with which the gear-wheel d' on the end of the roller A is made to engage as the roller A is lowered toward roller A'.

The operation of my invention is as follows: The roller A² is first placed in the position to accomplish the curvature desired by moving the cored handles E E to the proper places and allowing the sliding catches F F to fasten in the notches on the arcs F' F', that have the same number opposite on the index. Then the end of the sheet of metal to be curved is placed between the rollers A and A', the rollers being separated, as shown in Fig. 2. Then the roller A is made to approximate the roller A' by means of the adjusting-screws b b, and the gear-wheel d' is made to engage the gear-wheel d, and the roller A' is made to turn the roller A. As the sheet of metal is drawn through the rollers (the metal being caught between the rollers by reason of the lowering of roller A) it comes in contact with roller A², which has already been set to make a longer or shorter curve, as desired.

It will be seen from the foregoing description that the means employed are simple and accurate.

I am aware that the means for approximating and separating the rollers by means of sliding or movable journals and adjusting-screws and eccentric-journals are neither of them new, and I make no claim upon them separately.

What I claim as new and of my invention is—

In a sheet-metal-bending machine, the combination, substantially as specified, of the standard C, stationary roller A', and vertical movable roller A, and adjusting-screws b, with the movable roller A², eccentric-bearings B', notched and indexed arcs F', the cored handles E, and spring-actuated catches F, said handles being secured to the eccentric-bearings B', and the catches F, adapted to engage the notches in the arcs F', whereby the roller A² is adjustably movable in relation to the rollers A A', for the purposes set forth.

OLIVER POCOCK.
